UNITED STATES PATENT OFFICE.

JAMES E. CARPENTER, OF BERLIN, WISCONSIN, ASSIGNOR TO THE BERLIN MACHINE WORKS, OF SAME PLACE.

WOOD-POLISHING MACHINE.

SPECIFICATION forming part of Letters Patent No. 392,663, dated November 13, 1883.

Application filed September 30, 1887. Serial No. 251,149. (No model.)

To all whom it may concern:

Be it known that I, JAMES E. CARPENTER, of Berlin, in the county of Green Lake, in the State of Wisconsin, have invented new and useful Improvements in Machines for Polishing Wood, of which the following is a specification.

My invention relates to the well-known machines used for sandpapering, and especially to the adjusting devices for determining the parallelism of the sand-cylinder and the table which overlies the same, and which is commonly known as the "sand-guard," and also for regulating the depth of the cut to be given by the action of the sand-paper, and also to the mechanism for imparting an axially-longitudinal reciprocating motion to the revolving sand-cylinders, and to other parts designed for perfecting the operation of the machine, which will be hereinafter specifically pointed out.

As the general construction of such machines is well known, it will be unnecessary to set out more than the portions of the machine to which my improvements are applied.

The machine to which my improvements are specially applicable is formed of a main frame carrying a series of sand-paper cylinders, the periphery of which, appearing through a slot 30 in the sand-guard, acts upon a board which is introduced between positively-actuated feed-rolls carried part in the main frame and part in a vertically and independently adjustable frame, which also carries the pressure-rolls.

In the annexed drawings, making part of this specification, Figure 1 is a perspective view of my improved machine; Fig. 2, a side view, partly in section; Fig. 3, a longitudinal sectional view through one of the cylinders.

The same letters are employed in all the figures in the designation of identical parts.

The main frame carries a series of preferably three sand-paper cylinders, marked, respectively, No. 1, No. 2, and No. 3. More or fewer may be employed. The adjusting mechanism, hereinafter described, is applicable to each of the cylinders and its sand-guard, and is duplicated to any extent required. To describe its application to one will therefore be 50 sufficient.

Immediately under the shaft of each cylinder I place a through-shaft, A, which projects at both ends beyond the main frame, and carries on the overhung ends swinging arms B, which are pivoted at one end to the frame, and are adjustable at the free end vertically by means of the set-screws B' passing through lugs on the main frame. The adjustment of these set-screws regulates the position of the shaft A. When this adjustment has been made, 55 the arm B is confined further by a set-screw, B'', passing through a slot therein. On the same shaft A, I place, immediately inside the frame on both sides, other arms, C, Figs. 2 and 3, which are attached to the shaft by set-screws C', so that when the arm is turned at one end it will turn the shaft and the corresponding arm at the other end of the through-shaft A. The arm C is actuated on one side by a bar, C', attached thereto by a bolt. This 60 bar C' extends out through the main frame at the end of the machine, and is fastened to an extension, C'', by a bolt, C''. The extension is surrounded by a sleeve, C'', the two parts being connected by a male and female screw, and 65 the sleeve is turned by a hand-wheel, C''. As the sleeve is confined in the frame, so that it cannot move lengthwise when it is turned, the bar C' will be drawn or thrust so as to swing the arm C. 70

The arm C is formed with a segmental eccentric-slot, C', to receive a wrist-pin, D, attached to the vertically-sliding frame E, which carries one end of the sand-cylinder shaft, G. This frame slides in ways attached to the main 75 frame, and is raised or lowered by the action of the eccentric-slot C' on the wrist-pin D. A corresponding arm and frame at the other end of the cylinder-shaft G and shaft A similarly raise or lower that end of the cylinder-shaft. 80 As shown in Figs. 1, 2, and 3, a slot, E', in the frame E permits this to be done without interference by the shaft A, which passes through the slot and also allows the shaft to be independently adjusted by means of the arms B. 85

Similar mechanism is attached to all the sand-cylinders, so as to permit their independent adjustment in relation to the sand-guards F for the determination of the amount of the cut. These sand-guards are also independ- 90 95 100

ently adjustable, with a view to establishing and maintaining their perfect parallelism in reference to the surface of the cylinders. They are iron tables or plates covering that portion 5 of the space inclosed within the main frame, which is immediately over the sand-cylinders, and are slotted so as to permit the peripheries of the sand-cylinders to appear above the plane of their upper surface. Unless these 10 surfaces are parallel in all parts to the cutting-surface of the cylinder the work will be imperfect, and as heretofore constructed the part of the table opposite the middle of the slot was liable to sag under the pressure of the 15 board, being unsupported except at the corners. Struts F' are attached to the main frame by dovetailed recesses, and through the struts are passed, at one or more places, rods F², formed with threads. A nut, F³, above the 20 strut, and another below, F⁴, determine the elevation of the point of the rod, which bears against a flange, F⁵, on the sand-guard F. One such rod may be used by attaching a collar or head, F⁶, to support two of the tables F where 25 their edges adjoin.

To support the corners of the table or sand-guard F, I form it with lugs F⁷ to rest upon the heads of set-bolts F⁸, passing through lugs F⁹ on the main frame, and with square ends 30 beneath the lug F¹⁰ to receive a wrench by which they may be turned. Through the lugs F⁷, I tap set-screws F¹¹, the lower ends of 35 which are received in a recess formed in the upper end of the set-bolt F⁸, and so lock the latter when it has been properly adjusted.

It is desirable that the sand-cylinders shall have imparted to them a longitudinally-reciprocating movement, as well as one of rotation. The former is provided in the following manner: Horizontal shafts H' are hung on bearings on the outside of the main frame, carrying on the outer end a bevel-pinion, which 40 may be driven by a corresponding miter-wheel on a transverse driving-shaft, or said shaft may be otherwise driven from any convenient part. This shaft carries an eccentric, H, which revolves within a frame, H², placed within the jaws of an arm, I, which confine it 45 sideways, while they permit it to play freely in the other direction. I' is a cap confining the frame H². The arm I is attached to a collar, I', surrounding the cylinder-shaft G. This collar is confined endwise between rings I², fastened to shaft G by set-screws which turn 50 with said shaft, while the shaft rotates within the collar I'. The eccentric H imparts to the shaft G a longitudinal reciprocating motion in its box L, in which it revolves.

K is a bracket bolted to the main frame, 55 which carries the boxes K' of the shaft H.

It has hitherto been usual to use a series of sand-cylinders of the same size and revolving at the same speed to dress and polish the wood; but in these machines the work is imperfect, as the wood is left with a sort of fine 60 fuzz on its surface. To remove this and more

perfectly polish the surface of the wood, I introduce another preferably smaller and more rapidly moving sand-cylinder covered with finer sand-paper, acting with a light touch 70 upon the surface of the wood to remove such fuzz.

The sand-paper is cut into sheets of sizes proper for covering the entire surface of the cylinders and attached thereto in any suitable 75 manner.

What I claim as my invention, and desire to secure by Letters Patent, is—

1. In combination with the sand-cylinder and shaft of a wood-polishing machine, a 80 through-shaft, A, carrying the cylinder-bearings, and the arms B and set-screws for adjustably supporting the ends of the shaft, substantially as set forth.

2. In combination with the sand-cylinder 85 and shaft, the through-shaft A, frame E, having a stud-pin, D, and the adjustable slotted arm C, regulating the position of the cylinder, substantially as set forth.

3. In combination with the sand-cylinder 90 G' and shaft G, the through-shaft A, adjustable arms B, swinging arms C, and slotted frame E, whereby the ends of the shaft A can be independently adjusted and both ends of the sand-cylinder can be equally and simultaneously moved, substantially as set forth. 95

4. In combination with the sand-cylinder and shaft G, the vertically-adjustable frame E, arm C, bar C², and sleeve C⁵, threaded thereon and confined so as to have only a motion of rotation, substantially as set forth. 100

5. In combination with the sand-cylinder and shaft G, the vertically-adjustable frame E, arm C, rod C², sleeve C⁵, confined to the main frame, and hand-wheel C⁷, substantially 105 as set forth.

6. In combination with the sand-cylinder and sand guard or table F, adjusting-bar F², arranged to support the table between its ends, and strut F', supporting said bar adjustably, 110 substantially as set forth.

7. In combination with the sand-cylinder, main frame, and sand guard or table F, the adjustable supporting-bolt F⁹, and locking-bolt F⁸, substantially as set forth. 115

8. In combination with the table or sand guard F, independently adjustable at each end, the sand-cylinder G, independently adjustable at each end and also simultaneously adjustable at both ends, substantially as set 120 forth.

9. In combination with the sand-cylinder and shaft G, the eccentric H, shaft H', and sleeve I', and arm I, which receive a reciprocating movement from the eccentric and impart it to the cylinder, substantially as set 125 forth.

10. In combination with the sand-cylinder and shaft G, the eccentric H, shaft H', frame H², arm I, sleeve I', and rings I², substantially 130 as set forth.

11. In a machine substantially such as

shown, the combination, with a sand-cylinder, of a sand guard or table, F, slotted to receive the periphery of the sand-cylinder and adjustably supported at the corners and intermediate so as to permit its vertical adjustment and also maintain it rigidly in plane, substantially as set forth.

In testimony whereof I have hereunto set my hand in the presence of two subscribing witnesses.

JAMES E. CARPENTER.

In presence of—
R. MASON,
L. D. FORBES.
